UNITED STATES PATENT OFFICE.

GEORGE REECE, OF WOLLASTON, MASSACHUSETTS, ASSIGNOR TO REECE FOLDING MACHINE COMPANY, OF PORTLAND, MAINE.

FOLDING-MACHINE FOR COLLARS, &c.

No. 889,858.

Specification of Letters Patent.

Patented June 2, 1908.

Application filed November 9, 1900, Serial No. 35,942. Renewed February 20, 1903. Serial No. 144,329.

To all whom it may concern:

Be it known that I, GEORGE REECE, a citizen of the United States, and resident of Wollaston, county of Norfolk, State of Massachusetts, have invented an Improvement 5 in Folding - Machines for Collars, &c., of which the following description, in connection with the accompanying drawings, is a specification, like letters on the drawings 10 representing like parts.

My invention is an improvement in collar and cuff folding machines and has reference more particularly to the collapsible or retractable former or die, both in its construction 15 and operation. I have applied my invention to the type of machine shown in my application No. 20,125 filed June 13, 1900, and my invention has for its leading objects the provision of extreme rigidity and mutual 20 supporting strength in the coöperating parts as well as smoothness and facility of movement; also the provision of special means for folding oblique ended blanks; and the provision of simple mechanism for adjustability to 25 accommodate different sizes without liability of getting out of order or in a wrong position.

The various details of construction and advantages in operation of my invention will be more fully pointed out in the course of the 30 following description, reference being had to the accompanying drawings and illustrations of the preferred embodiment of my invention, and the latter will be more particularly defined in the appended claims.

35 In the drawings Figure 1 represents in side elevation sufficient parts of the machine to render my invention intelligible. Fig. 2 is an enlarged top plan view of the upper portion of the former or die. Fig. 3 is a longitudinal vertical section thereof taken on the line 3—3, Fig. 2. Figs. 4 to 7 are similar end views of the die and its operative parts showing the successive positions assumed thereby in the process of folding a blank. 40 Figs. 8 and 9 are vertical cross-sections taken respectively on the lines 8—8 and 9—9, Fig. 3. Figs. 10 and 11 are horizontal sections showing the lower portion of the die, and illustrating the positions assumed thereby in 45 relation to the receiving bed of the machine. Fig. 12 is a similar view showing the shape of die required for a cuff.

It will be understood that the frame A of the machine, bed A', and general supporting

and operating means of the die D may be of 55 any suitable kind for the purpose, although I prefer and have therefore illustrated the form herein shown in which the die is carried by swinging arms d loosely pivoted on a shaft d' and operated by a bell crank d² connected at 60 one end by a link d³ with the projecting end d⁴ of said arms, and at its other end provided with a roll d⁵ actuated by a cam d⁶ of the driving shaft, and said die is further actuated by slides d⁸, d⁹ forked at their rear ends d¹⁰ 65 so as to be guided by the shaft d' as clearly shown in Fig. 1, and having intermediate their ends rolls d¹², d¹³ traveling in and respectively operated by path cams d¹⁴, d¹⁵ of a cam d¹⁶, driven by the shaft d'. The moving 70 parts of the die D are carried by a frame d¹⁷ on rods d¹⁸ slidingly mounted in said frame. Said rods are secured to a carrier bar or plate d¹⁹ provided with projecting friction rolls d²⁰, and also with a bell-crank d²¹ pivoted 75 thereto at d²² on the top edge of said plate which stands vertical as is clearly seen in the end views. The plate d¹⁹ forms a back support for the collapsible or end-wise shifting parts of the die, being recessed at its front 80 side d²³ so as to form directing grooves and supporting ledges for slide blocks or carriers d²⁴ which are retained by headed studs d²⁵ operating freely in slots d²⁶ in the plate d¹⁹. At their upper edges the carriers d²⁴ are provided with pins or rolls d²⁷ operating in cam slots d²⁸ provided in bridge pieces d²⁹ mounted in the frame d¹⁷ adjacent the opposite ends 85 thereof, whereby upon forward or backward movement of the rod d⁹ and plate d¹⁹ the carriers, d²⁴, will be contracted or brought towards each other. The general features thus far explained, aside from the special construction of the die itself, are also disclosed in 90 my before-mentioned copending application 95 and are therein claimed. These carriers are themselves grooved similarly to the plate d¹⁹ and support the rear and front blade holders d³⁰, d³¹, to the lower ends of which are secured forming portions or blades d³², d³³ of the die. 100

The carriers d²⁴ are slotted longitudinally at d³⁴ and to them are adjustably secured the holders d³⁰, d³¹, by means of bolts or nuts d³⁵, see Fig. 9, and the holders d³¹, d³¹ are vertically slotted at d³⁶ to permit vertical movement, being also for a like purpose vertically slotted at d³⁷, d³⁸ to accommodate retaining pins d³⁹ which maintain the two holders 105

against each other and pins d^{40} projecting from the back holders which support the upper ends of lifting springs d^{41} secured at their lower ends at d^{42} to the front holders.

5 Retained by guides d^{43} on the upper edge of the front holder d^{31} is a cam-bar d^{44} having cam surfaces d^{45} which coöperate with the rolls d^{20} to depress the front holders and front part of the die against the tendency of the 10 springs d^{41} to raise the same, said bar being operated by engagement therewith at d^{46} of the free end of the bellcrank d^{21} which is pivoted at d^{47} to the slide d^8 .

An intermediate piece d^{48} operated by a 15 spring d^{49} , and otherwise the same as the part d^{31} is preferably provided for filling the gap between the end parts of the former when the latter is adjusted lengthwise for different sizes of blanks.

20 The operation of the parts thus far described is as follows: The parts come down on the blank in the same relative position as shown in Figs. 1 to 3, this being the normal or intermediate position of the parts. The 25 front fold having been made by suitable folding blades, not shown, the two slides d^8 and d^9 are moved backwardly to the position Fig. 4 by the cams d^{14} , d^{15} , thereby causing the cams d^{28} to retract or draw inwardly the end parts 30 of the die or former, carrying their edges simultaneously from beneath the front edge and end folds, and thereupon the shifting movement to the right of the bar d^{44} permits the front portion of the former to rise as 35 shown in Fig. 5, whereupon the slide d^9 is moved forward restoring the die to its intermediate position and expanded condition as indicated in Fig. 6 where the rear portion of the former is in place for the infolding of the 40 rear edge of the blank, which operation is then accomplished by suitable folding blades not shown. The rear fold having been made the die is again collapsed, this time, however, by a forward movement, the parts being 45 thereby brought into the position shown in Fig. 7 where the parts are entirely removed from all the folds of the blank; and from this position the die is raised and while being raised the parts are restored to their normal 50 position as shown in Fig. 1.

It will be seen that although the movements are more or less complicated the mechanism provided by my invention is exceedingly simple and the parts are so arranged that they coöperate with each other to give mutual strength and form practically a solid piece as is clearly evident from Figs. 4 to 7. The result is that the die will stand an enormous amount of straining and pounding and wear and is not liable to get out of order.

It may be well to explain that this class of machines is required to work rapidly and under great pressure as the proper folding of the linen and cotton blanks must be accom-

plished on the heated bed before the cloth has time to dry, and moreover the folds must be firmly creased in order that they may maintain their folded condition. It will be apparent therefore that not only 70 must the proper movement be provided but it is equally important that a sufficiently strong and accurate mechanism be provided capable of accomplishing the peculiar and severe and yet delicate work required of them. Also the construction explained maintains the parts in the same solidity and compactness of position irrespective of their various adjustments, it being understood that these adjustments are not merely advisable but are necessary in this art. 75

Referring now to Figs. 10 to 12 where the blade-like portion of the former or the parts of the die proper are shown in detail in plain view, I will explain further peculiarities of 80 the construction and operation of the former.

Figs. 10 and 11 show the former or die as shaped for folding oblique ended articles such as a collar band, and the only peculiarity of construction needing explanation and which has not yet been explained is the feature of having the ends of the front portions d^{33} extended rearwardly as indicated at d^{51} , so as to encompass or pass around the 90 ends of the rear parts d^{32} more or less. The purpose of this construction will be understood when it is borne in mind that when the front edge and two ends of the blank are simultaneously infolded, the parts being in the position shown in Fig. 1 and Fig. 10 that the die moving as it does as shown in Figs. 4 to 7 could not get out from beneath the front portion of the end folds if the rear portion d^{32} of the die extended to the end of the 95 blank because the die having collapsed or moved rearwardly and then again moved forwardly and expanded as shown in Fig. 6, the ends of the rear portion d^{32} would be beneath the end folds in the same position which they would have occupied during the folding of said end folds and then the rear fold having been made and it being remembered that the ends of the blank are oblique as shown, the forward movement 100 of the die into the position shown in Fig. 7 would simply move the rear portion d^{32} along beneath the end folds without extricating the ends of said die from beneath said folds. 110

By making the ends of the front portion 120 d^{33} extend rearwardly, however, in the shape shown, all this difficulty is obviated in a simple and practical manner, as the rearward movement of the die to the position shown in Fig. 11 is accompanied by an upward movement of said front portion of the die so that when the die is again restored to its intermediate position, shown in Fig. 6, the front portion of the die is entirely out of engagement with the blank, although the rear 125 130

portion is in engagement with the blank and is in the required extended position for the infolding of the rear edge of the blank, and yet is so shaped at its ends that when it is 5 subsequently collapsed and moved forward to the position shown in Fig. 7 there is no liability of catching in the end folds and disturbing them.

While I have herein described my invention in all the details thereof as shown, I do not intend to restrict myself thereto, as in 10 many respects my invention is capable of a wide variation in details of construction, and therefore I do not limit myself otherwise 15 than as expressed in the claims.

It will be noticed that certain features herein shown are not claimed, the reason being that they form the subject matter of claims in my aforesaid co-pending application, as for instance the pin-and-slot construction in combination with operating 20 parts for longitudinally contracting the die, and the swinging support carrying the collapsible die and operating means for said die 25 and said support.

Having described my invention, what I claim as new and desire to secure by Letters Patent, is:—

1. In a machine for folding collars and the 30 like, a die or former comprising a supporting carrier extending in a vertical plane, and independent holders, provided with the blade portions of the die, all standing on edge and nested solidly and compactly together in 35 mutual contact throughout their length and provided with overhanging portions whereby the pressure strains brought upon the die are mutually sustained by all of said parts.

2. In a machine for folding collars and the 40 like, a die or former comprising a supporting plate, recessed longitudinally at one side, a carrier formed to fit said recess and mounted to slide longitudinally therein, one forming portion of the die being carried and moved 45 with said carrier, a second forming portion of the die mounted on but having movement independent of said first mentioned forming portion.

3. In a machine for folding collars and the 50 like, a die or former made up of a plurality of parts mutually movable for contracting lengthwise and for moving up and down simultaneously, said parts including a main supporting plate, a plurality of holders, each 55 provided with a forming portion of the die proper, and means for carrying said holders, the said mentioned parts being placed edge-wise vertically and held together side by side in a compact form for giving mutual support 60 and solidity to the die in its various operations, and means for independently operating said parts.

4. In a machine for folding collars and the 65 like, a die or former comprising two die hold-

ers, said holders having contacting flat surfaces extending substantially in a vertical plane, a carrier frame for supporting the die as a whole, a cam bar mounted above one of said holders and provided with cam surfaces, coöperating parts carried by said frame for engaging said cam surfaces, and means for giving relative shifting movement to said cam bar and said coöperating parts for moving the adjacent holder and its forming portion vertically.

5. In a machine for folding collars and the like, a die or former comprising a frame, a plate support mounted movably in said frame and depending vertically below the 80 frame, a plurality of holders, each provided with a die portion, and mounted compactly at a vertical side of said plate support, means for shifting said plate support in said frame, and means for shifting said holders relatively 85 to said plate support.

6. In a machine for folding collars and the like, a die or former containing a movable supporting plate standing vertically and having a horizontal longitudinal slot, a carrier, 90 a die portion carried thereby, said carrier being held rigidly against said supporting plate, and means movable in said slot for retaining the parts in constant engagement throughout their movements.

7. In a machine for folding collars and the like, a die or former containing a movable supporting plate standing vertically and having a horizontal longitudinal slot, a carrier, a die portion carried thereby, said carrier 100 being held rigidly against said supporting plate, means movable in said slot for retaining the parts in constant engagement throughout their movements, a second die portion, a holder therefor, said holder having 105 vertical slots, and means occupying said vertical slots for maintaining said holder in constant engagement with the other parts of the die, and permitting vertical movement while preventing longitudinal movement relatively 110 to the adjacent parts.

8. In a machine for folding collars and the like, a die or former comprising a frame, a plurality of die holders, said die holders having adjacent plane surfaces in contact with 115 each other, and means for maintaining said holders in unchanging longitudinal position with relation to each other and permitting them to change in vertical position, means for moving one of said die holders vertically, and 120 means for moving the other of said die holders, and thereby both of them, longitudinally.

9. In a machine for folding collars and the like, a die or former, comprising a supporting plate, a carrier mounted against one side 125 thereof, means maintaining said plate and carrier in constant contact and permitting relative longitudinal movement, a die holder mounted against one side of said carrier and longitudinally adjustable thereon, a second 130

die holder mounted against the outside face of the other die holder, means securing said two holders together permitting vertical movement by preventing longitudinal movement of one relatively to the other, and a die portion carried by each holder.

10. In a machine for folding collars and the like, a die or former comprising a plurality of parts, including a pair of holders at each end, said holders being maintained constantly together side to side or face to face, thereby preventing spreading or lateral movement of the forming parts, said pairs being mounted to move longitudinally towards each other, means for moving one of said holders vertically independent of the other, means for moving said pairs of holders toward and from each other, each of said holders being provided with a forming portion of the die, said forming portions at their ends having an oblique portion for forming the oblique end folds of a blank such for example as a collar band, the outer ends of one of each of the pairs of forming portions being extended to constitute said oblique portion, and having its said extended end extending across the end of the adjacent forming portion.

11. In a machine for folding collars and the like, a die or former having a plurality of forming portions arranged to conform to the contour of the blank to be folded, and including at each of the ends of the die a pair of forming portions, one of which has its outer end or forming edge extending in an oblique direction across the end of the adjacent forming portion, and means for contracting said end portions towards each other, and

means for raising the corresponding parts of each of said pairs dis-simultaneously. 40

12. In a machine for folding collar blanks and the like, a die or former comprising a supporting plate, and a carrier, extending downwardly, and independent holders for the blade portions of the die, all standing on edge and nested solidly and compactly together in mutual contact face to face, means whereby the pressure strains upon the die are mutually sustained by all of its parts, said die blade portions, and mechanism for carrying and moving the said die or former in coöperation with the other parts of the machine. 45

13. A high speed power operated folding machine for collar blanks or the like, said machine comprising in combination an arm fitted so as to be capable of swinging upwardly and downwardly, and a die located at the extremity of said swinging arm, the said die comprising expanding and contracting portions or members, means for contracting and expanding the same, the said portions or members fitted and connected for co-action with the other parts through upwardly extending plates, and said plates, 60 the same arranged in face contact with each other for the purpose of mutual support and to enable the die to withstand the pounding received in practice. 65

In testimony whereof I have signed my name to this specification, in the presence of two subscribing witnesses.

GEORGE REECE.
